INVENTOR:

Edward H. Godshalk,
BY *John A. Niederhein,*
ATTORNEY.

UNITED STATES PATENT OFFICE.

EDWARD H. GODSHALK, OF PHILADELPHIA, PENNSYLVANIA.

FORMER FOR DRESS-TRIMMINGS, &c.

SPECIFICATION forming part of Letters Patent No. 287,662, dated October 30, 1883.

Application filed April 28, 1883. (No model.)

To all whom it may concern:

Be it known that I, EDWARD H. GODSHALK, a citizen of the United States, residing in the city and county of Philadelphia, State of Pennsylvania, have invented a new and useful Improvement in the Manufacture of Ladies' Dress-Trimming, Ornaments, Gimp, &c., which improvement is fully set forth in the following specification and accompanying drawings, in

10 which—

Figure 1 is a top or plan view of a former for the manufacture of trimmings, &c., embodying my invention. Fig. 2 is a side elevation thereof, partly sectional. Fig. 3 is an

15 illustration of the design produced.

Similar letters of reference indicate corresponding parts in the several figures.

My invention consists of a former for ladies' dress-trimmings, ornaments, &c., constructed 20 of a flexible pad, to which is permanently affixed a series of pins arranged relatively to the design of the trimming, &c., to be formed, braid, gimp, &c., being passed or fitted around the pins and sewed together, whereby uniform 25 designs may be produced and the work accomplished in an expeditious manner.

Referring to the drawings, A represents a piece of leather or other suitable material of 30 flexible nature, to which is permanently affixed a series of projecting pins, B, which are arranged relatively to a desired design for trimmings, ornaments, &c., such design being a leaf, palm, scroll, &c., the pins being headed and sufficiently separated to permit the pas-

sage around them of the braid, gimp, &c., 35 which being accomplished, the contiguous or adjacent parts are sewed together, whereby the shape of the design is preserved, and the same is then removed from the pins, it being noticed that uniform and superior work may 40 be produced.

It will be seen that the pad may be conveniently handled and bent as desired, so as to stretch or contract the different lengths of the braid, gimp, &c., as the work progresses, 45 according to the necessity of the case, and the pad may be reused, being strong and durable. The pins are headed at both ends, whereby they are securely connected with the pad at their lower ends, and the braid, &c., will not 50 slip from the upper ends.

Having thus described my invention, what I claim as new, and desire to secure by Letters Patent, is—

1. As a new article of manufacture, a former 55 for trimmings, ornaments, &c., consisting of a flexible pad and pins permanently secured thereto, said pins being headed and arranged harmoniously in the form of designs, substantially as and for the purpose set forth.

2. The former for trimmings, &c., consisting of a flexible pad and connected pins, both ends thereof being headed, substantially as and for the purpose set forth.

E. H. GODSHALK.
